UNITED STATES PATENT OFFICE.

JAMES ROONEY, OF WASHINGTON, DISTRICT OF COLUMBIA.

AEROPLANE CONSTRUCTION.

1,132,686.

Specification of Letters Patent.

Patented Mar. 23, 1915.

Application filed December 4, 1914. Serial No. 875,501.

To all whom it may concern:

Be it known that I, JAMES ROONEY, a citizen of the United States, residing at Washington, in the District of Columbia, have invented certain new and useful Improvements in Aeroplane Constructions, of which the following is a specification.

The present invention relates to certain new and useful improvements in aeroplanes and has for its object to provide an aeroplane construction which embodies novel features of design whereby a maximum strength and rigidity is obtained for the weight of the materials employed, and which admits of the planes being readily warped to balance the machine.

A further object of the invention is to provide an aeroplane in which the main frame may be formed of metal, thereby providing a machine which is excellently adapted for use in connection with military operations since there is no danger of the frame being splintered and broken so as to disable the machine when struck by a bullet or flying projectile.

With these and other objects in view, the invention consists in certain novel combinations and arrangements of the parts as will more fully appear as the description proceeds, the novel features thereof being pointed out in the appended claims.

For a full understanding of the invention, reference is to be had to the following description, and accompanying drawings, in which:

Figure 1 is a front elevation of a conventional form of biplane constructed in accordance with the invention. Fig. 2 is a detail perspective view of one end of the biplane with portions broken away and shown in section to illustrate more clearly the details of construction. Fig. 3 is a plan view of a portion of one of the planes with portions broken away to illustrate more clearly the construction. Fig. 4 is an enlarged sectional view through one of the frame joints, said section being taken on the line 4-4 of Fig. 3. Fig. 5 is a similar view taken on the line 5-5 of Fig. 3. Fig. 6 is a transverse sectional view through one of the planes, taken on the line 6-6 of Fig. 3. Fig. 7 is a transverse sectional view through one of the wooden trusses, said section being taken on the line 7-7 of Fig. 6. Fig. 8 is an enlarged detail view showing the manner of connecting the tension wires to the end cross bars of the planes. Fig. 9 is an enlarged detail view of one of the entering edges, portions being broken away. Fig. 10 is a similar view of one of the trusses for the planes, and Fig. 11 is a detail view of the controlling lever for warping the planes.

Corresponding and like parts are referred to in the following description and indicated in all the views of the drawings by the same reference characters.

For the purpose of illustration the invention is shown as embodied in a conventional form of biplane, although it will be obvious that the method of constructing the planes and frame may be used upon any airship including one or more supporting planes in its organization.

Referring to Fig. 1, the character A designates an upper plane and B a lower plane which are supported by a main frame including a series of uprights 1, the middle uprights being formed with downward extensions 1^a upon which the conventional skids 2 and wheels 3 may be mounted.

The main supporting frame includes primarily the uprights 1 and the longitudinal frame members 4, both sets of members being hollow and formed of metal and the longitudinal frame members 4 being arranged within the interior of the respective planes A and B so as to offer no resistance to the passage of the machine through the air. In the preferred construction the uprights 1 are formed of square tubes while the longitudinal frame members 4 are formed of round tubes. These frame members 4 are formed in sections which are interposed between the tubular uprights 1 and have their ends abutting against the flat sides thereof. For the purpose of providing a rigid joint between the uprights 1 and longitudinal frame members 4, short tubular pins 5 are provided and these tubular pins are passed transversely through the uprights 1 so as to project laterally upon opposite sides thereof. The projecting ends of these tubular pins 5 are received within the ends of the longitudinal frame members 4, and since the frame members act under compression a very effective form of joint is obtained. The diameter of the tubular pin 5 is less than the diameter of the tubular frame members 4 and the projecting ends of the former may have sleeves or bushings 6 fitted thereon so as to produce a tight joint with the ends of the frame members. These

bushings 6 may be secured in position by the conventional pins 7. By using this form of joint the necessity of unduly weakening the uprights 1 by drilling large holes therein 5 to receive the large frame members 4 is avoided.

The supporting planes A and B are identical in their construction. Each of the planes is formed with a series of intermediate cross bars 8 and end cross bars 8^a, said cross bars being mounted upon the various uprights 1 and the intermediate cross bars being rigidly mounted upon the uprights while the end cross bars have a pivotal 15 mounting and are adapted to be tilted up and down for the purpose of warping the plane. Each of the cross bars in its detail construction is formed of an intermediate metal strip 9 which passes through the upper 20 right 1 and has wooden strips 10 applied to opposite sides of the projecting ends thereof. As indicated more clearly by Figs. 4 and 5, the portions of the metal strips 9 of the cross bars within the tubular uprights 1 are formed with openings receiving the tubular joint pins 5, and spacing collars 11 are fitted upon the tubular pin upon opposite sides of the metal strips 9 so as to be interposed between the said metal strip and 25 the sides of the tubular upright 1 and prevent the latter from being crushed by the pressure of the ends of the longitudinal frame members 4 against the sides thereof. Fig. 5 illustrates the joint between the 30 frame members 4 and an intermediate upright 1 in which the metal strip 9 of the cross bar 8 is rigidly connected to the upright, while Fig. 4 illustrates the joint upon an end upright 1 in which the metal strip 9 35 of the cross bar 8^a passes loosely through slots 12 in the upright 1 and is pivoted upon the joint pin 5 so as to have the necessary up and down swinging movement for warping the plane.

The several cross bars 8 and 8^a of each plane are connected by a series of spaced and parallel tension wires 14. These wires 14 pass through the intermediate cross bars 8 and have their extremities adjustably connected to the end cross bars 8^a. In the present instance, as illustrated more clearly by Fig. 8, the ends of the wires 14 are shown as passed through the heads of eye bolts 15 and secured by sleeves 16, said eye bolts passing through the cross bars 8^a and having nuts 17 applied to the threaded ends thereof. With this construction it will be obvious that by tightening the nuts 17 the wires 14 can be readily placed under any desired amount of tension.

The entering edge 18 and tail 19 are each split longitudinally to provide the respective complementary sections 18^a and 19^a which can be applied to the outermost wires 14 from opposite sides thereof. These mem-

bers 18 and 19 are interposed between the ends of the various cross bars 8 and 8^a and abut loosely against the same so as to act under compression and prevent bending of the cross bars due to excessive strain or tension in the wires. The rear ends of the members 18 and 19 have the longitudinal edges thereof rabbeted at 18^b and 19^b respectively to receive the extremities of the upper and lower strips 20 of the wooden truss members. These truss members are arranged parallel to the cross bars and at suitable intervals between the same. Each of the truss members includes a thin vertical web 21 shaped to give the desired cross section to the plane, and upper and lower strips 20 which fit over the edges of the web and have the extremities thereof secured to the rabbeted portions of the respective members 18 and 19. The web 21 is provided with suitable openings through which the wires 14 and longitudinal frame members 4 pass. As indicated by Fig. 2, the usual fabric covering 22 is applied to the frame thus provided.

The ends of the longitudinal frame members 4 project beyond the uprights 1 at each end of the frame and are connected by truss wires to the respective end cross bars 8^a. Intermediate portions of the truss wires 24 95 may pass loosely through the projecting ends of the frame members 4, while the ends of the truss wires are suitably connected to the cross bars. In Fig. 3 the extremities of the wires 24 are shown as 100 threaded and passed through the cross bar 8^a, the said threaded extremities of the wires having nuts 25 fitted thereon so that by tightening or loosening the nuts the tension in the wires can be increased or decreased as 105 desired. A fabric covering 26 is designed to be applied to the truss wires 24 and projecting ends of the frame members 4 so as to increase the effective area of the supporting frames.

For the purpose of simultaneously warping the two superposed planes, the two end cross bars 8^a at each end of the aeroplane may be connected by the tie wires 27. One of the end cross bars 8^a at each end of the machine, preferably the upper one, has the operating cables 28 connected to the end portions thereof. These operating wires 28 pass around the wheels of a double pulley 29 which is pivotally mounted upon the upright 1. At a suitable point toward the middle of the machine the various operating cables 28 are connected to a controlling lever 30 on opposite sides of the pivot 31 thereof, as indicated by Fig. 11. With this construction it will be apparent that when the operating lever 30 is swung in one direction one of the cables 28 at each end of the machine will be taken in and the other cable let out with the result that the ends of the plane 130

will be warped. The plane will be warped in one direction when the operating lever 30 is moved to the right and in the opposite direction when the operating lever is moved 5 to the left. The construction of the plane itself is admirably adapted to warping, since the tension wires 14 hold the parts tightly together but at the same time provide joints which are sufficiently loose so that they do 10 not interfere with the warping operation.

Having thus described the invention, what I claim as new and desire to secure by Letters Patent, is:—

1. An aeroplane construction including a 15 frame, cross bars mounted thereon, a series of tension wires connecting the cross bars, edge pieces interposed between the cross bars and bearing loosely at their ends against the cross bars so as to offer no resistance to 20 the warping of the plane, transverse truss members connecting the edge pieces, and a fabric covering applied to the edge pieces and truss members.

2. An aeroplane construction including a 25 frame, cross bars mounted thereon, a series of tension wires connecting the cross bars, edge pieces loosely interposed between the cross bars and divided longitudinally to provide complementary sections adapted to 30 be applied to the outermost tension wires, transverse truss members connecting the edge pieces, and a fabric covering applied to the edge pieces and truss members.

3. An aeroplane construction including a 35 frame, cross bars mounted thereon, a series of tension wires connecting the cross bars, means for adjusting the tension in the said wires, edge pieces loosely interposed between the cross bars and mounted upon the outer 40 tension wires so as to be carried thereby, a series of transverse truss members connecting the edge pieces and each including a vertical web through which the tension wires pass and upper and lower flat strips connected to 45 the edge pieces, and a fabric covering applied to the edge pieces and truss members.

4. An aeroplane construction including a 50 frame formed of tubular uprights and tubular longitudinal frame members interposed between the uprights and abutting against the same, joint pins passing through the uprights and having the projecting ends thereof fitted within the abutting ends of the longitudinal frame members, cross bars passing 55 through the uprights and mounted upon the joint pins, and a supporting plane mounted upon the cross bars.

5. An aeroplane construction including a

frame formed of tubular uprights and tubular longitudinal frame members interposed 60 between the uprights and abutting against the same, joint pins passing through the uprights and having the projecting ends thereof fitted within the abutting ends of the longitudinal frame members, cross bars passing 65 through the uprights and provided with openings receiving the joint pins, spacing collars mounted upon the joint pin between the cross arms and the sides of the uprights so as to prevent crushing of the uprights, and 70 a supporting plane mounted upon the cross arms.

6. An aeroplane construction including a 75 frame formed of tubular uprights and tubular longitudinal frame members interposed between the uprights and abutting against the same, tubular joint pins passing through the uprights and having the projecting ends thereof received within the ends of the longitudinal frame members, bushings upon the 80 ends of the tubular joint pins, cross bars passing through the uprights and provided with openings receiving the joint pins, spacing collars fitted upon the joint pins between the cross bars and the sides of the uprights 85 to prevent crushing of the latter, and a supporting plane mounted upon the cross bars.

7. An aeroplane construction including a 90 frame formed of tubular uprights and tubular longitudinal frame members interposed between the uprights and abutting loosely against the same, joint pins passing through the uprights and having the projecting ends thereof fitted in the abutting ends of the 95 longitudinal frame members, cross arms mounted upon the uprights, and a supporting plane mounted upon the cross bars and including tension members connecting the cross bars to hold the uprights against the 100 ends of the longitudinal frame members.

8. An aeroplane construction including a frame formed with intersecting tubular frame members, one set of frame members abutting loosely against the opposite frame 105 member, and a joint pin passing through the said opposite frame member, the projecting ends of the joint pin being fitted within the abutting ends of the other frame members.

In testimony whereof I affix my signature 110 in presence of two witnesses.
